UNITED STATES PATENT OFFICE.

STANLEY MOORE DEWEY, OF RUTHERFORD, NEW JERSEY.

CALENDAR-BLOTTER.

SPECIFICATION forming part of Letters Patent No. 701,169, dated May 27, 1902.

Application filed September 3, 1901. Serial No. 74,188. (No model.)

To all whom it may concern:

Be it known that I, STANLEY MOORE DEWEY, a citizen of the United States, and a resident of Rutherford, in the county of Bergen and 5 State of New Jersey, have invented a new and Improved Calendar-Blotter, of which the following is a full, clear, and exact description.

The object of my invention is to provide a 10 new and improved calendar-blotter which is simple and durable in construction and arranged to combine both a convenient blotter and a daily calendar in such a manner that a new blotting-sheet or a new calendar can 15 be readily inserted and securely held in position for convenient and handy blotting of frequent sheets and for displaying the day of the week, month, and year, together with suitable advertising matter.

20 The invention consists of novel features and parts and combinations of the same, as will be fully described hereinafter and then pointed out in the claims.

A practical embodiment of my invention is 25 represented in the accompanying drawings, forming a part of this specification, in which similar characters of reference indicate corresponding parts in both the views.

Figure 1 is a perspective view of the improvement with parts broken out, and Fig. 30 2 is a longitudinal sectional elevation of the same.

The improved device consists, essentially, 35 of a frame A, preferably in the shape of a block having a segmental bottom and a flat top, and on the ends of the said frame A are arranged clips B B, alike in construction and each connected to the frame by a transverse pivot C, as plainly indicated in Fig. 1. Each 40 of the clips B is pressed on by the free ends of a spring D, secured to the frame at the top thereof, preferably in a recess, as indicated in Fig. 1. Each clip B is in the form of an open pocket, into which extends the corresponding end of the frame A, and each clip 45 consists of a bottom member B', an integral top member B², and integral end pieces B³, the latter carrying the pivot C. The bottom member B' and the end pieces form with the 50 end of the frame A a pocket for receiving and holding the corresponding end of the blotting sheet or sheets E, and the said top member

B² and the end pieces B³ also form a pocket for receiving the ends of superimposed sheets F, held on the top of the frame A and bearing legends representing a daily calendar or other matter, such as advertisements and the like. The top members B² also form clamping-plates, pressing on the top of the uppermost of the sheets F, so as to securely hold 60 the said superimposed sheets in position stretched on the top of the frame A. The blotter-paper E is stretched over the segmental bottom surface of the frame A and is held in this position by the members B', as the 65 tendency of the spring C is to swing the clips B in an upward direction to cause the bottom members B' to bear and press against the ends of the blotting-sheet E.

When it is desired to renew the blotting- 70 sheet E, the operator can readily disengage the blotting-sheet from the clips and insert a new one, and the uppermost sheet F can be readily removed at the expiration of each day, so as to display the date of the following day. 75 When the sheets F have been used up, a new set of sheets may be readily introduced and secured in position on the top of the frame A by the members B² pressing on the uppermost sheet, as previously explained. 80

Having thus described my invention, I claim as new and desire to secure by Letters Patent—

1. A blotter, comprising a frame, and clamping devices mounted on said frame, and each having two members which are provided with two separate gripping-surfaces adapted to respectively engage the under face of a blotting-sheet on the bottom of said frame, and the upper face of superimposed sheets on 90 the top of said frame. 85

2. A calendar-blotter, comprising a frame having a segmental bottom, a blotting-sheet on said bottom, a calendar on the top of said frame, and a clamping device yieldably supported on the frame and provided with two members which are formed with gripping-surfaces adapted to respectively engage the under face of the blotting-sheet and the top face of the calendar. 95

3. A calendar-blotter, comprising a frame having a segmental bottom, a blotting-sheet on said bottom, a calendar on the top of said frame, and clamping devices individually 100

fitted to the ends of the frame, each clamping device having members disposed at an angle to each other and formed with gripping-surfaces arranged to hold the blotting-sheet 5 and the calendar separately and removably in place on the frame.

4. A calendar-blotter, comprising a frame having a segmental bottom, a blotting-sheet on said frame, a calendar on the top of said 10 frame, and spring clamping-clips at the ends of the frame and each provided with separate gripping-surfaces disposed at an angle to one another, said gripping-surfaces of each clip adapted to individually hold the end portions 15 of the blotting-sheet and the similar portions of the calendar.

5. A calendar-blotter, comprising a frame having a segmental bottom, a blotting-sheet on said frame, a calendar on the top of said 20 frame, clips at the ends of the frame and provided with angularly-disposed members which have gripping-faces adapted to individually

hold the blotting-sheet and said calendar in position on the frame, and springs pressing said clips and holding both members thereof 25 in active engagement with the blotter and the calendar.

6. The combination with a frame, of clips held on the ends of said frame, each clip having angularly-disposed members which are 30 provided with gripping-faces arranged in opposing relation to the under side and the top face of the frame respectively, a clamping-plate at the top of the frame, and springs pressing the clips for both surfaces thereof 35 to occupy active relation to the frame.

In testimony whereof I have signed my name to this specification in the presence of two subscribing witnesses.

STANLEY MOORE DEWEY.
